(57) **CLAIM**

The ornamental design for a control panel for a coordinate input device, as shown and described.

DESCRIPTION

FIG. 1 is a front elevation view of a control panel for a coordinate input device showing our new design;

FIG. 2 is a rear elevation view thereof;

FIG. 3 is a left side elevation view thereof;

FIG. 4 is a right side elevation view thereof;

FIG. 5 is a top plan view thereof, wherein the bottom plan view is the same as the top plan view;

FIG. 6 is a top front left isometric view thereof; and,

FIG. 7 is a close up view of portion A-A of FIG. 6.

The broken lines shown in FIGS. 1-7 illustrate environmental subject matter and form no part of the claimed design.

1 Claim, 5 Drawing Sheets
